DESIGN FOR A BLOUSE

Lizzie Hafler, Los Angeles, Calif., assignor to Sidney S. Rice, Jr., and Arthur S. Klein, copartners doing business as Tailor Maid Blouses, Los Angeles, Calif.

Application October 24, 1938, Serial No. 80,643

Term of patent 3½ years

To all whom it may concern:

Be it known that I, Lizzie Hafler, a citizen of the United States, residing at Los Angeles, California, have invented a new, original, and ornamental Design for a Blouse, of which the following is a specification, reference being had to the accompanying drawing, forming a part thereof.

Figure 1 is a front view of a blouse, showing my new design.

Fig. 2 is a rear view thereof.

I claim:

The ornamental design for a blouse, as shown.

LIZZIE HAFLER.
